(57) **CLAIM**

The ornamental design for a delivery box, as shown and described.

DESCRIPTION

FIG. 1 is a front perspective view of a delivery box showing our new design;

FIG. 2 is a rear perspective view thereof;

FIG. 3 is a front view thereof;

FIG. 4 is a rear view thereof;

FIG. 5 is a top view thereof;

FIG. 6 is a left side view thereof; and,

FIG. 7 is a right side view thereof.

The broken lines shown in the drawings depict portions of the delivery box and form no part of the claimed design.

1 Claim, 7 Drawing Sheets

	EU Patent application 008749295-003 filed on Nov. 5, 2021.	Office Action issued in CN Application No. 202230252604.0 dated Jul. 5, 2023.
	EU Patent application 008749295-004 filed on Nov. 5, 2021.	Olydon Insulated Heated Delivery Bag, Available Online at: https://www.amazon.ca/OLYDON-Insulated-Heated-Delivery-Handle/dp/B08NB2MQHN?th=1 , Date First Available: Jun. 2, 2022.
	EU Patent application 008749295-005 filed on Nov. 5, 2021.	Dometic DeliBag, Available Online at: https://www.dometic.com/en-us/professional/mobile-delivery-solutions/food-delivery/dometic-delibag-12-331--323325 , Date First Available: Jun. 2, 2023.
	EU Patent application 008749295-006 filed on Nov. 5, 2021.	Restriction Requirement issued in Design U.S. Appl. No. 29/837,304 dated Aug. 25, 2023.
	GB Patent application 6204725 filed on Apr. 26, 2022.	International Preliminary Report on Patentability received in PCT Application No. PCT/EP2021/087152, dated Aug. 24, 2023.
	GB Patent application 6204726 filed on Apr. 26, 2022.	International Preliminary Report on Patentability received in PCT Application No. PCT/EP2021/087798, dated Aug. 24, 2023.
	GB Patent application 6204727 filed on Apr. 26, 2022.	Office Action issued in CN Application No. 202130343187.6 dated Sep. 6, 2023.
	GB Patent application 6204728 filed on Apr. 26, 2022.	Office Action issued in CN Application No. 202130343235.1 dated Sep. 6, 2023.
	GB Patent application 6204729 filed on Apr. 26, 2022.	Ex-Parte Quayle Office Action issued in Design U.S. Appl. No. 29/837,304 dated Dec. 11, 2023.
	GB Patent application 6204730 filed on Apr. 26, 2022.	Notice to Grant issued in CN Application No. 202230252604.0 mailed on Jan. 17, 2024.
	Notification of Grant Issued in China Application No. 202130343234.7 dated Mar. 22, 2022.	
	International Search Report and Written Opinion received in PCT Application No. PCT/EP2021/087152, dated Apr. 12, 2022.	
	Design U.S. Appl. No. 29/837,304, filed May 4, 2022 titled "Delibox light-courier deliver-NN-NN".	
	International Search Report and Written Opinion received in PCT Application No. PCT/EP2021/087069, dated May 6, 2022.	
	International Search Report and Written Opinion received in PCT Application No. PCT/EP2021/087798, dated May 9, 2022.	
	Office Action issued in German Patent Application No. 102021212256.6 dated Jun. 10, 2022.	
	Chinese Patent Application No. 202230253654.0 filed on Apr. 29, 2022.	
	Chinese Patent Application No. 202230252604.0 filed on Apr. 29, 2022.
